Attorney

UNITED STATES PATENT OFFICE

EDWARD T. HAILS, OF MONTGOMERY, ALABAMA, ASSIGNOR TO SUPER SAN TOWEL CABINET COMPANY, OF MONTGOMERY, ALABAMA, A CORPORATION OF ALABAMA

SANITARY ROLL-TOWEL CABINET

Application filed February 16, 1928. Serial No. 619,462.

My invention relates to an improvement in roll towel cabinets.

One object of my invention is to make the cabinet sanitary and to this end I design the 5 cabinet so that the clean and soiled towel rolls are kept separated, preferably being disposed in separate compartments in the cabinet, and no part which contacts with the soiled towel can touch the clean towel.

10 A further object of my invention is to so control the feeding of the clean towel from its roll that it cannot slip relatively to the feed means, and this will result in the friction and take-up rolls always moving to the 15 same extent. By this means I prevent an increase length of the exposed towel loop being drawn out from the cabinet, for if slippage is permitted by a friction roll the length of the towel exposed will tend to increase each 20 time it is pulled or jerked so that in time it will hang down to the floor.

A further object of my invention is to provide means associated with the clean towel roll means about which the towel is so threaded and which are so relatively movable that a hard or sudden jerk on the clean towel will cause them to grip it positively and hold it 25 against slippage relative to a friction roller which is geared to a friction roller for the 30 soiled towel take-up roll.

A further object is to so mount the take-up roll and its friction roll and to so thread the towel around them that there is no tendency of towel slippage at this point when 35 it is pulled or jerked, and a positive take-up is at all times insured.

A further object is to provide the friction rolls with a simple and inexpensive covering which will not be affected by moisture and 40 to this end I utilize rolls, preferably wooden rolls, covered with ordinary roofing.

A further object of my invention is to provide the cabinet with an indicator controlled by the movement of the center or axis of the 45 clean towel roll to indicate the time the cab-

inet is empty and at all times the approximate amount of towel unused.

My invention further comprises the novel details of construction and arrangements of parts, which in their preferred embodiment 50 only are illustrated in the accompanying drawings which form a part of this specification, and in which:—

Fig. 1 is a front elevation of the cabinet broken away to show half of the interior in 55 elevation.

Fig. 2 is a vertical cross-section view taken on the line 2—2 of Fig. 1.

Fig. 3 is a detail view showing one side wall of the cabinet and illustrating the manner of threading the towel, the three rolls being shown separated in full lines to better illustrate the manner of threading the towel thereon, and in dotted lines to better illustrate how the towel is gripped to prevent 65 slippage.

Similar reference numerals refer to similar parts throughout the drawings.

In the embodiment of my invention illustrated I show a cabinet 1, made of any suitable material and having a front door 2 and a horizontal partition 3 subdividing the cabinet into upper and lower towel compartments 4 and 5. The upper compartment 4 is adapted to receive the clean towel roll 6 70 and has, as the preferable means for guiding said towel roll, grooves or slots 7 in the end walls of this compartment, which grooves receive the axis of the roll. The grooves open through the front of the cabinet and extend 75 rearwardly and downwardly on an incline towards a friction roll 8 which is journaled in fixed bearings in one end wall 9 of the cabinet and in a vertical front to rear partition wall 9^a, which is spaced sufficiently from 80 the other end wall of the cabinet to permit a gear 10 to be mounted on the overhung end of the axis 11 of this friction roll. The walls 9 and 9^a of the compartment 4 are also provided with guide grooves or slots 12 which are 85 90

inclined downwardly towards the friction roll 8 and which removably and adjustably support a guide roller 13. This guide roller is normally disposed under the towel roll 6 and in front of the feed roll 8 in such relation to both that when a towel 14 is unwound from the under surface of the roll 6 and passed rearwardly over and about the friction roll 8, it can be passed upwardly and over the 10 guide roll 13 and then downwardly over a guide 15 past the front edge of the partition 3, and thence through an opening 16 at the lower forward portion of the cabinet below the door. After forming the service loop, 15 the soiled towel passes upwardly through a slot 17 in the rear portion of the bottom 18 of the cabinet and thence between a pair of smoothing guides 19 upwardly and forwardly over and about a friction roll 20, and then 20 downwardly and rearwardly under the soiled towel take-up roll 22. The friction roll 20 is mounted like the friction roll 8 in the walls 9 and 9^a and has on its overhung axis a gear 21 meshing the gear 10. The gears are typi- 25 cal of any suitable drive which will connect the friction rollers so that they will move together with the same peripheral speeds. This friction roll 20 is mounted above the take-up roll 22 on which the soiled towel is rewound 30 and which has a spring 23, connected at both ends to its axis and secured overhead to the partition or rear wall of the cabinet, which acts to draw the take-up roll firmly up against its respective friction roll. The towel passes 35 rearwardly about and under its take-up roll and the position of the latter is such relatively to the guides 19 that the towel forms almost a complete bite about the friction roll 20.

Both friction rolls 8 and 20 are preferably 40 made of wooden rollers having a covering layer of composition roofing 24 applied thereto so as to give them a moisture proof, durable frictional surface.

An index pointer 25 projects through a 45 suitable opening in the top 26 of the cabinet and is operated by a hinged rod 27 having journaled in its lower end a roller 28 disposed with its axis parallel with the axis of the towel roll 6 and resting by gravity thereon. 50 The roller 28 will descend in following the diminishing diameter of said roll 6, as the towel is unwound therefrom, and as it drops the hinged rod 27 will, in proportion to the diminishing diameter of the towel roll 6, 55 move the index hand across an indicator 29 mounted at the front of the cabinet in convenient position to be viewed by the user and having suitable marks or symbols displayed thereon so as to indicate the approximate 60 amount of clean towel remaining unused in the cabinet and to give notice when the cabinet is empty.

In operation, it is to be observed that the 65 towel forms almost a complete loop or bite about both the friction rolls 8 and 20, thus

giving it the maximum frictional engagement therewith. Bearing in mind that the upper guide roller 13 is free to move towards and engage the friction roller 8, it follows that when the towel is pulled or jerked down this roll is drawn into tight towel gripping contact with the friction roll, thereby increasing the frictional engagement of the towel therewith to such a degree that it is practically impossible for the towel to slip about its 75 upper friction roller 8. This being true, it follows that as the towel is drawn out this friction roll 8 must be at all times proportionately rotated, and this roll being geared to the friction roll 20, will transmit to the latter the same peripheral movement as that of the roll 8 and will rewind the exact amount of soiled towel that is drawn off of the roll 6 onto the take-up roll 22. This is of very great importance in preventing the exposed 80 towel loop from being increased by reason of slippage until it becomes too long.

The partition wall 3 and the relative position of the guide 15 and the slot 16 keep the clean towel out of contact with any part of the soiled towel, and the clean towel being stored in the overhead cabinet compartment is kept entirely sanitary. The rolls 6, 13 and 22 can all be readily removed by sliding them along their respective guides and out through the front of the cabinet when it is desired to thread on a clean towel, and as the towel is used the index hand will at all times indicate the extent to which it is used and will give notice when the cabinet is empty. The small guides 19 will serve to straighten out the soiled towel and get it in condition to be rewound smoothly on the take-up roll 22. While, if desired, the take-up roll 22 may be held to its work and the bite formed in the soiled towel for the friction roll 20 exactly as shown in the compartment 4, nevertheless the spring arrangement shown gives a simple and compact organization. Should the gravity action be used in the lower compartment 5 of the arrangement would be identical as in compartment 4 except the roll 13 would then be disposed at the rear instead of at the front of the take-up roll.

Though I have described with great particularity the details of the embodiment of the invention herein shown, it is not to be construed that I am limited thereto, as changes in arrangement and substitution of equivalents may be made by those skilled in the art 110 without departing from the invention as defined in the appended claim.

Having thus described my invention, what I claim as new and desire to secure by Letters Patent, is:—

A towel cabinet having inclined slots 115 therein, a support for a clean towel supply, a roll adapted for frictional contact with a towel web, and the cabinet having an opening through which said towel web may be drawn, 120

and means for preventing a towel user from causing an overthrow of toweling from said supply, said means including a guide roll having its upper surface above the lower surface of said friction roll, said guide roll having journals pivoted in said inclined slots, the construction being such that a hard sudden pull on said towel web will cause said guide roll to move along said slots toward said friction roll and cooperate therewith to grip the towel between the said rolls.

10 In testimony whereof I affix my signature.
EDWARD T. HAILS.
